UNITED STATES PATENT OFFICE.

WILFRED G. JOHNSON, OF ELYRIA, OHIO, ASSIGNOR TO THE COLSON COMPANY, OF ELYRIA, OHIO, A CORPORATION OF OHIO.

DESIGN FOR A CASTER.

Application filed March 2, 1927. Serial No. 20,944. Term of patent 14 years.

To all whom it may concern:

Be it known that I, WILFRED G. JOHNSON, a citizen of the United States, residing at Elyria, in the county of Lorain and State of Ohio, have invented a new, original, and ornamental Design for Casters, of which the following is a specification, reference being had to the accompanying drawings, forming part thereof.

The figure is an elevational view of a caster showing my new design.

I claim:

The ornamental design for a caster, as shown.

In testimony whereof, I hereunto affix my signature this 25th day of February, 1927.

WILFRED G. JOHNSON.
